HAT MAKING

Application filed March 5, 1930. Serial No. 433,237.

This invention relates to the manufacture of hats, and more especially to men's hats, such as felts, derbies, and straws, wherein so-called sweat-bands are employed inside of 5 the hat where contact is made with the head. The bands are usually made of leather, which is finished on the outer or grain side to resist the action of perspiration and oil. The bands are sewed to the inside of the hat near their 10 lower edges, which lie practically flush with the brim. The sutures pass through the marginal portion of the crown, where they are concealed by the usual band or ribbon employed for ornamentation. Men's hats such 15 as described invariably undergo discoloration or staining at the lower marginal portions of the ornamental band or ribbon which is usually made of silk or other expensive fabric. In most cases, after only a comparative 20 short use of a hat, discoloration or staining of the ornamental band or ribbon becomes so pronounced that the fastidious user is compelled to discard the hat, even though it may be otherwise serviceable, or 25 to undergo the expense of equipping the hat with a new ornamental band or ribbon.

We have observed that the discoloration or staining of the ornamental band is traceable to the perspiration and oil working its way 30 through the apertures formed in the sweat-band and hat material by the needle used in the sewing operation. Such discoloration or staining is apt to be particularly unsightly in the case of felt hats, wherein there is more or 35 less capillarity in the felt to augment the passage of the discoloring agents to the ornamental band. In an attempt to overcome this difficulty, a rubber-calendered taping is sometimes sewed to the lower edge of the sweat- 40 band, and this taping is stitched to the marginal portion of the crown. Aside from the fact that this expedient adds another stitching operation, it is only a makeshift cure, since perspiration and oil find their way 45 through the apertures formed in the sweat band, taping, and hat material to the ornamental band.

In accordance with the present invention, a more effective barrier is formed against the 50 penetration of perspiration and oil to the

ornamental band. This barrier is produced by applying rubber latex to the inside of the sweat-band at least over that zone or area where the sutures are to pass therethrough, and permitting the latex to dry or set before 55 the stitching operation. After the aqueous content of the latex has dried out, it is found that a continuous film or membrane of rubber has been coagulated on the band. The rubber thus deposited is characterized by an elasticity sufficiently marked so that after a needle and thread have been passed therethrough, it undergoes contraction against the thread body to seal completely the aperture formed in the operation. The tightness with 60 which the rubber embraces the thread body is shown by the fact that light does not pass through a sweat-band carrying a film of rubber deposited from latex and through which sutures have been passed.

With the foregoing and other features and objects in view, the present invention will now be described more specifically in conjunction with the accompanying drawings, 65 wherein

Figure 1 represents a transverse section through a usual type of felt hat made in accordance with the present invention.

Figure 2 is an enlarged fragmentary section through that portion of the hat where 70 the sweat-band is located.

Figure 3 is a similar view of a modification.

Figure 4 shows in perspective a band carrying a film of rubber only at the stitching zone.

Figure 5 is a fragmentary perspective of a band carrying a film of rubber over its entire surface.

Figure 6 represents a greatly enlarged section on the line 6-6 of Figure 4.

Figure 7 shows in perspective the shape which the band assumes when assembled with a hat.

The sweat-band which is treated in accordance with the present invention may be 85 of a type customarily employed in hat manufacture, and consists of a strip of leather which has been cut to a length and curvature to fit nicely around the inside of a hat with its lower edge substantially flush with the 100

inner edge of the brim. The outside of such a band is the grain side, which may be suitably finished, as with a lacquer, to resist the action of perspiration and oil. The inside, 5 which is unfinished, is in a rough or napped condition. As shown in Figure 4, the latex may be applied to the inside of such band *a* along a marginal zone or area *b*, where stitching of the band to the body or crown 10 of the hat is to be effected. Any suitable applicator, such as a brush, may be used, it being preferable to apply two or more coats of latex in order to ensure a continuous film of rubber. The latex is preferably permitted 15 to dry out between successive coatings, and the film of rubber is completely dried out, preferably in a warm atmosphere, before assembling the band with the hat. The film of rubber deposited on the band adheres ten- 20 aciously thereto by reason of the roughness or nap of the inside. If desired, the latex may be applied over the entire inside of the band, as shown in Figure 5, in which case passage of perspiration and oil through the 25 band over its entire surface is prevented, even when the leather by itself is so porous as to permit such passage. Owing to the nature of the film and the manner in which it is applied as above described, it becomes di- 30 rectly incorporated with, or a part of the leather body as hereinafter defined in the claims "integral" therewith. The band is placed inside the hat, with the film of rubber carried thereby adjacent to the inside mar- 35 ginal portion of the crown *c*, as shown in Figures 1, 2, and 3, whereupon it is sewed in place, the sutures *s* being passed through the lower marginal portion of the band carrying a film of rubber and the crown portion 40 immediately above the brim *d*. The usual ornamental band *e* may then be tacked as usual to the hat, with its lower edge terminating at the upper face of the brim so that the sutures *s* outside the crown are concealed 45 thereby.

The latex which we employ may be the usual article of commerce, which is preserved with suitable agents such as ammonia, and has a solids content of about 30% to 35%, but 50 it may be more or less concentrated, depending upon the thickness of coating which it is desired to produce in a single application and the ease of application with the particular applicator employed. If desired, suitable 55 fillers, pigments, or dyes may be added to the latex, and when tackiness in the rubber film is to be avoided, vulcanizing agents, such as sulphur, may be added thereto, so that after the application and drying out of the latex 60 the rubber film may be more or less vulcanized under the application of heat. So-called vulcanized latices may be employed to advantage, as in such case drying of the latex results in a more or less vulcanized rubber 65 film which is non-tacky.

One of the major advantages of the present invention is that we are enabled to improve greatly the lasting qualities of the ornamental bands of hats at an exceedingly low cost. The amount of latex used in forming the rubber film on the band is so small as to be virtually negligible and its application and drying involves little labor cost and inexpensive instrumentalities. While the latex may be applied at the hat factory, nevertheless it is more practical that this be accomplished at a central point, as by a manufacturer of the bands who is in a position to carry out large scale operation. The bands thus reach the hat manufacturer in condition 70 for assembly with the hats. 75

We claim:

1. As an article of manufacture, a sweat-band designed for stitching to hats, the inside of said band carrying an integral film 85 of rubber coagulated from latex at least over the longitudinal zone where said band is to be stitched to the hat.

2. As an article of manufacture, a leather sweat-band designed for stitching to hats, 90 the inside of said band being rough and carrying an integral film of dried-out latex at least over the longitudinal zone where said band is to be stitched to the hat, said film being characterized by sufficient elasticity to 95 contract against a thread body passed therethrough.

3. A hat comprising a body, a sweat-band sewed to such body and the inside of which has an integral film of dried-out latex at least over the longitudinal zone where the sutures 100 pass therethrough, and an ornamental band fixed to the body and concealing said sutures.

4. A method of making hats equipped with sweat-bands and ornamental bands, which comprises applying liquid rubber latex to the inside of the sweat-band at least over the longitudinal zone where it is to be sewed to the hat, then drying out the latex, sewing the sweat-band to the hat with the sutures passing through to the dried-out latex, and fixing the ornamental band in place to conceal the outside sutures. 110

5. As an article of manufacture, a sweat-band designed for stitching to hats, the inside of said band carrying over its entire surface an integral layer of dried-out latex which is characterized by sufficient elasticity to contract against a thread body passed therethrough. 115

In testimony whereof we have affixed our signatures.

FRANK M. BARTLETT.
